UNITED STATES PATENT OFFICE.

THOMAS TRACY, OF MILLBURN, NEW JERSEY.

LIQUID-FUEL BURNER.

Application filed June 5, 1925. Serial No. 35,201.

This invention relates to new and useful improvements in vaporizers, and particularly to devices for vaporizing liquid fuel.

One object of the invention is to provide a device in which the liquid fuel will be quickly vaporized and gasified before being delivered to the burner.

Another object is to provide a simple device of this character wherein the flow of vapor is readily and properly regulatable.

Another object is to provide a device of this character which may be easily and quickly taken apart for cleaning and adjustments.

Other objects and advantages will be apparent from the following description when taken in connection with the accompanying drawing.

In the drawing:

Figure 1 is an elevation of a burner equipped with the present vaporizer.

Figure 2 is a top plan view of the same.

Figure 3 is an enlarged vertical sectional view on the line 3—3 of Figure 2.

Referring particularly to the accompanying drawing, 10 represents a burner, which is mounted on one end of a gas conduit 11, and extending upwardly from said end of the conduit is an apertured member 12. A

tee coupling 13 is provided with a depending apertured lug 14 which receives a bolt 15 therethrough, said bolt being also disposed through the member 12, whereby to secure the coupling 13 in proper position.

Engaged on the other end of the coupling is a cap 16, and formed on the intermediate portion of the coupling, and depending therefrom, is a nipple 17, to which is adapted to be attached any suitable conduit for con-

veying liquid fuel thereto. Screwed into the lug carrying end of the coupling 13 is one end of an oil vaporizing and gasifying tube 18, and engaged on the other end of the tube is a cap 19, the outer end of which is re-

duced, as shown at 20, and internally threaded to receive therein the hollow plug 21. The cap 19 is formed with a chamber 22, between the reduced end thereof and the adjacent end of the tube 18. Disposed with-

in the tube 18, and having a terminal flange 23 which is clamped between the adjacent end of the tube and the cap 19, is a sleeve 24, said sleeve being of an external diameter slightly less than the interior diameter of the said tube. Disposed longitudinally within the tube 18 is a rod 25, which has an

external diameter equal to the diameter of the sleeve 24, and held in spaced relation to the bore of the coupling 13 by the slightly smaller opening in the cap 16, through which said rod passes. The outer end of the rod is provided with a hand wheel 26. The other end of the rod 25 is reduced in diameter and externally threaded to be received in the sleeve 24. Beyond the threaded end of the rod there is a further reduction in the diameter of the rod, and screwed into the end of this further reduced portion of the rod is one end of a needle valve 27, which is adapted to be moved longitudinally toward and away from the opening in the cap 19, and into and out of said opening, whereby to regulate the flow of gas. The sleeve 24 is provided with longitudinal slots 28 whereby the gas, generated from the liquid fuel in the space between the tube 18 and the rod 25 may pass into the chamber. The other end of the conduit 11 turns upwardly and inwardly toward the burner 10, and into this end of the conduit the cap 19 is disposed, for delivering gas to the conduit. The gas then passes through the horizontal portion of the conduit, and thence upwardly to the burner. By grasping the hand-wheel and turning the rod 25, said rod will, by reason of its threaded engagement with the sleeve 24, and further by reason of the fact that the sleeve is held against rotation by the tube 18 and cap 19, move longitudinally in the tube 18, whereby to cause the needle valve 27 to regulate the opening in said cap 19.

It will be noted that the tube 18 extends transversely of the burner 10, in position to be heated by the flame from the said burner. This heat from the burner will cause the liquid fuel, flowing from the tube 18, externally of the rod 25, to become vaporized and gasified, and flow into the chamber of the cap 19, by means of the slots 28, and thence out through the plug 21 to the conduit and the burner.

The small space between the tube 18 and rod 25 permits the liquid fuel to spread out in a thin layer, so that vaporization will be more rapid, and as the burner 10 continues to heat the tube 18, the vapor will become gasified as it proceeds toward the outlet end of the vaporizer, and is constantly delivered to the burner 10. More gas will be generated than the burner 10 can burn, therefore such excess gas will flow to the burners 30.

In opposite sides of the horizontal portion of the conduit 11 there are formed the nipples 29 to which are adapted to be connected additional burners, which receive excess gas generated in the tube 18. Each of the additional burners, which are shown at 30 is provided with a valve operable by the hand device 31.

What is claimed is:

- 10 In a burner for liquid fuel, a vaporizing and gasifying tube having a lateral liquid fuel inlet at one end and a gas outlet at the other end, an internally threaded and longitudinally slotted sleeve in the outlet end of the tube, a plug adjustable in said outlet end and having a minute opening longitudinally therethrough, a rod longitudi-
- 15

nally and centrally within the said tube and spaced therefrom to provide a narrow circumscribing fuel vaporizing and gasifying 20 passage between the inlet and outlet of the tube, one end of the rod being threaded into said sleeve, a burner beneath the tube and being connected with the gas outlet end thereof, a controlling needle valve on the 25 sleeve engaging end of the rod movable in said minute opening, and means for rotating the rod to thread the same through the sleeve and move the needle into and out of the minute opening and cover and uncover 30 said slots.

In testimony whereof, I affix my signature.

THOMAS TRACY.
